(57) **CLAIM**

The ornamental design for a x-ray bucky wall stand, as shown and described.

DESCRIPTION

FIG. 1 is a perspective view of a x-ray bucky wall stand showing our new design;

FIG. 2 is a front side view of the x-ray bucky wall stand shown in FIG. 1;

FIG. 3 is a rear side view of the x-ray bucky wall stand shown in FIG. 1;

FIG. 4 is a left side view of the x-ray bucky wall stand shown in FIG. 1;

FIG. 5 is a right side view of the x-ray bucky wall stand shown in FIG. 1;

FIG. 6 is a top view of the x-ray bucky wall stand shown in FIG. 1; and,

FIG. 7 is a bottom view of the x-ray bucky wall stand shown in FIG. 1.

The portions of the x-ray bucky wall stand shown in broken lines form no part of the claimed design.
